THOMAS H. SANFORD INVENTOR.

BY

Richard B. Owen
ATTORNEY.

UNITED STATES PATENT OFFICE.

THOMAS H. SANFORD, OF ALEXANDER CITY, ALABAMA, ASSIGNOR OF ONE-FOURTH TO
LEMUEL B. COLEY, OF ALEXANDER CITY, ALABAMA.

BRAKE-SHOE.

1,395,365.

Specification of Letters Patent.

Patented Nov. 1, 1921.

Application filed December 10, 1920. Serial No. 429,682.

To all whom it may concern:

Be it known that I, THOMAS H. SANFORD, a citizen of the United States, residing at Alexander City, in the county of Tallapoosa 5 and State of Alabama, have invented certain new and useful Improvements in a Brake-Shoe, of which the following is a specification.

This invention relates to a brake shoe and 10 has for its principal objects the production of means to connect a brake shoe and its head, so that they may be securely held together when so desired.

Another object of the invention is to generally improve upon brake shoes of this character by providing a device which will be of extremely simple, durable and inexpensive construction, one which is efficient and reliable in operation, and well adapted to the 20 purpose for which it is designed.

With these and numerous other objects in view, the invention resides in certain novel features of construction, and the combination and arrangement of parts as will be 25 hereinafter fully described and claimed.

In the drawing:

Figure 1 is a side elevation of the brake shoe and a portion of the brake head,

Fig. 2 is a vertical central section taken 30 through the brake shoe,

Fig. 3 is a plan view of the brake shoe, and

Fig. 4 is a section taken on the line 4—4 of Fig. 3.

Referring to the drawing by numerals it will be seen that 1 designates the brake shoe which may be of any preferred construction having the lugs 2, 3 and 4 projecting from the convex face thereof and it will 40 be noted by referring to Fig. 4 of the drawing that the lug 3 has slating side portions so as to be dove-tailed. The brake shoe 1 is provided with any preferred construction upon its wearing surface which is adapted 45 to engage the car wheel in a well known manner.

The brake head 5 is attached to the usual operating mechanism and comprises a curved body portion and upon the concave face 50 thereof is provided with the grooves 6, 7 and 8. A slot 9 communicates with the groove 6 from the under side thereof and a similar slot 10 communicates with the groove 8. A dove-tailed slot 11 communicates with

the groove 7 as is shown more clearly in 55 Fig. 4 of the drawing. A latch pocket 13 communicates with the groove 6 from the upper side thereof and has pivotally mounted therein the latch 14.

When it is desired to assemble the brake 60 shoe in connection with the brake head it will be readily seen that the latch 14 will be rotated so as to be wholly within the pocket 13. The lugs 2, 3 and 4 will then be placed centrally in the grooves 6, 7 and 8 and the 65 shoe 1 will then be pulled downwardly so that these lugs 2, 3 and 4 will fit in their respective slots 9, 11 and 10. The slot 11 and the lug 3 being dove-tailed as described it will be seen that it will be impossible to 70 pull the shoe from engagement with the head as long as the lug 3 is seated within the slot 11. In order to hold the various elements in the position just described the latch 14 will be forced into the position 75 shown in Fig. 3 of the drawing whereby the latch engages the lug 2 thus preventing the shoe and head from sliding in relation to each other so as to become disengaged. Thus it will be seen that the device may be 80 easily assembled and to disassemble same all that will be necessary is to knock the latch 14 from engagement with the lug 2 and the device may then be easily disassembled in a manner which will be quite apparent. The keyway shown at 15 is used 85 when it is desired to use my shoe in connection with brake heads now commonly in use.

It is thought that the construction and operation of this invention will be readily 90 understood from the foregoing description taken in connection with the drawing without a more extended explanation. As numerous changes in form, proportion, and in the minor details of construction, may be 95 resorted to without departing from the spirit of this invention, I do not wish to be limited to the construction herein shown and described other than as claimed.

Having thus described my invention what 100 I claim as new is:—

A device of the class described comprising a brake shoe having a plurality of lugs projecting from the convex face thereof, one of said lugs being dove-tailed, a brake head 105 having a plurality of transverse grooves extending across the concave face thereof and one of said grooves provided with a dove-

tailed slot for receiving the dove-tailed lug on the brake shoe and the remaining grooves provided with slots for receiving the other lugs, a pocket formed adjacent one of said 5 grooves opposite its slot, and a latch pivotally mounted within said pocket for the purpose specified.

In testimony whereof I affix my signature in presence of two witnesses.

THOMAS H. SANFORD.
